PNEUMATIC THREAD CONTROL SYSTEM FOR LOOMS

Filed Oct. 11, 1950

UNITED STATES PATENT OFFICE

2,589,875

PNEUMATIC THREAD CONTROL SYSTEM
FOR LOOMSVictor F. Sepavich, Worcester, Mass., assignor to
Crompton & Knowles Loom Works, Worcester,
Mass., a corporation of Massachusetts

Application October 11, 1950, Serial No. 189,555

16 Claims. (Cl. 139—336.4)

1

This invention relates to pneumatic thread control systems of means for weft replenishing looms and it is the general object of the invention to provide means either to give a signal or effect loom stoppage upon failure of the pneumatic system.

A form of thread control system for weft replenishing looms which has gone into extensive use employs a pneumatic thread holder to tension the weft ends of reserve bobbins in the magazine, and also employs a collector for the waste threads left by the outgoing and incoming bobbins. In order to confine the threads within the collector the latter is generally provided with a screen which may become sufficiently clogged by the waste threads to prevent creation of a sufficient partial vacuum within the system for correct operation.

It is an important object of the present invention to provide a pneumatically controlled electric switch which upon closure can either give a signal, such as the illumination of a lamp, or effect loom stoppage. The switch is associated with a bellows unit connected through a small leak vent to the interior of the pneumatic system. So long as adequate subatmospheric pressures exist within the system the bellows unit will be in the non-switch closing position, but as soon as pressures within the container approach atmospheric pressure and are insufficient to attract the threads the bellows unit will expand and in doing so will close the switch.

In order that accumulated threads within the collector may be removed a door or cap or the like is provided which may be opened temporarily to afford access to the interior of the collector. If by oversight the cover should not be returned to its closed position subatmospheric pressures will not be developed within the container and in this event the bellows unit will operate to close the switch. If the switch controls a circuit containing a lamp the latter will remain illuminated and thus attract attention of the weaver who will then close the cover.

Ordinarily the drop in effective pressure within the system may not be sufficient to justify loom stoppage; in which event a signal will suffice, but if desired the switch can also cause loom stoppage.

With these and other objects in view which will appear as the description proceeds, the invention resides in the combination and arrangement of parts hereinafter described and set forth.

In the accompanying drawings, wherein a convenient embodiment of the invention is set forth:

2

Fig. 1 shows a side elevation of a weft replenishing loom having the invention applied thereto.

Fig. 2 is an enlarged plan view looking in the direction of arrow 2, Fig. 1.

Fig. 3 is an enlarged vertical section on line 3—3, Fig. 2.

Figs. 4 and 5 are vertical sections on lines 4—4 and 5—5, respectively, Fig. 3.

Fig. 6 is a section on line 6—6, Fig. 5.

Fig. 7 is an elevation of the switch carrier looking in the direction of arrow 7, Fig. 3.

Fig. 8 is a diagrammatic view of an electric circuit which can be used with the invention, and

Fig. 9 is a diagrammatic plan view showing the manner of pneumatically connecting and disconnecting the thread holder relative to the thread collector.

Referring to Fig. 1, the loom frame 1 supports top and bottom shafts 2 and 3 connected by gears 4 and 5 the latter of which may be twice the diameter of the former. A driving gear 6 loose on the top shaft 2 is driven by pinion 7 of the motor 8 suitably mounted on the loom. Clutch mechanism not shown herein is employed to connect the gear 6 to the top shaft 2 when it is desired to operate the loom.

A form of continuously operating pump 10 serving as a source of subatmospheric pressures is mounted in fixed position on a stand 11 supported by the loom frame and is driven by the gear 6. This pump is connected to a hose or flexible pipe 12 in which subatmospheric pressures are created by the pump. Hose 12 extends forwardly and is connected to a hollow thread collector designated generally at C.

As shown in the present instance the collector comprises a head 15, an elongated generally transparent hollow cylinder 16, and a cap or cover 17. The latter is mounted on lever 18 moving about a fixed pivot 19 and held normally in the closed position shown in Fig. 2 by a spring 20.

The head is associated with a pneumatic thread holder H for the weft ends W which extend from reserve bobbins in a magazine M, see Fig. 1. In the present instance this magazine is of the stationary type, but the invention is not limited to this form of magazine.

The holder is pneumatically connected to the interior of the container C at regular intervals by means of a lever 25 pivoted as at 26 to the head 15. This lever is connected by rearwardly extending rod 27 to another lever 28 rocking about a fixed pivot 29. A roll 30 at the bottom of lever 28 is moved to the left, Fig. 1, by a cam

31 secured to the top or crank shaft 2, once for each pick of the loom, to move the rod 27 rearwardly. A compression spring 32 interposed between the head 15 and the lever 25 normally rocks the latter and the rod 27 forwardly, or to the left as viewed in Fig. 2. An elastic tube 33 made for instance of soft rubber connects the holder H pneumatically to the interior of collector C and extends along a wall 34 forming part of head 15. An arm 35 of lever 25 is normally held by spring 32 against tube 33 to squeeze it against wall 34, see full lines in Figs. 3 and 9, to pinch the weft threads W passing into the tube.

When the lever 25 is in its normal position, as shown in full lines in Fig. 9, the thread holder H will be pneumatically disconnected from the interior of the container C and during this time the pump can create or build up subatmospheric pressures within the container. At each pick of the loom, however, upon rocking of lever 25 to the dotted line position shown in Fig. 9, the arm 35 will move to the dotted line position, Fig. 9, and tube 33 will return to its normal position to momentarily connect the holder H with the container for a brief interval and the weft threads W will be subject to a pressure tending to tension them, and when they are cut in usual manner incident to a weft replenishing operation they will be drawn as waste threads into the interior of the tube 16. The collector C may be made and operated in the general manner as set forth in prior Patent No. 2,431,556 issued to Hooper et al.

The head 15 is supported by a bracket 36 to a stationary part of the loom as by bolts 37, and is provided with an air chamber 38.

A lug 40 extending upwardly from the head 15 is connected to a flexible hose 41 leading to any approved form of pneumatic thread remover located between the magazine and the fabric being woven. The remover is not shown herein but may for instance be made as set forth in prior Patent No. 2,219,768 issued to Darwin.

During loom operation subatmospheric pressures will be built up within the container due to operation of the pump 10, and when the lever 25 is turned in a clockwise direction as viewed in Fig. 2 from its normal position due to cam 31, any loose waste threads remaining incident to a weft replenishing operation will be drawn from the thread holder and remover into the container. The weft ends W will also be tensioned. As set forth herein the hose 41 is not controlled by the lever 25 and any thread coming under control of the thread remover will be drawn immediately into the container without regard to the position of lever 25. The thread remover will ordinarily require a smaller stream of air than that required by the holder and it can therefore be connected directly to the interior of the container.

The weft ends and waste threads which enter the container will be attracted toward the cover 17. The latter is made with a cavity 45 communicating at one side thereof with a metal tube 46 connected to the hose 12. Extending across the other side of the cavity is a screen 47 against which the threads are drawn. When a large number of threads accumulate on the screen 47 there will be a drop in the effective pressures within that part of the container to the left of the cap or cover 17 as viewed in Fig. 2. Under these conditions the pneumatic system may fail to operate and the present invention provide means which will call attention to such failure.

The matter thus far described may be of usual construction and of itself forms no part of the present invention except as noted hereinafter.

The head 15 has a wall 50 into which is threaded the stem 51 of a bellows unit or pneumatic electric switch controller designated generally at B. The stem has a small leak vent 52 which communicates with the interior of a thin sheet metal resilient bellows 53 closed by an end wall 54. The stem 51 has a flange 55 which is secured by screws 56 to a retainer 57.

A switch carrier 60 made preferably of insulating material is held to the retainer by screws 61 and contains a normally open electric switch designated generally at S. As shown in Fig. 5 this switch has a contact 62 one end of which is fixed as at 63 to the carrier. Contact 62 is electrically connected to a bar 65 on the outer face of the carrier. This bar is connected electrically to the retainer, which is metal, by one of the screws 61, and in this way the contact 62 is grounded to the loom.

The switch S has a second contact 67 having a central prong 68 held to a stationary clip 69. Contact 67 also has resilient arms 70 which fit into angles 71 of a resilient operator 72 the lower end of which is fixed with respect to the carrier and is electrically connected to a contact 73 on the outer face of the carrier. This latter contact as well as the contact 67 is insulated by the carrier.

The resilient operator has a small button 75 which is in position for engagement with the end wall 54 of the bellows. The switch is normally open with the contact 67 out of engagement with the contact 62, but when the button 75 is pressed to the right as viewed in Fig. 3 a snap action of contact 67 occurs moving it away from its adjusting screw 76 into engagement with the contact 62. The latter has an adjusting screw 77. While a specific form of electric switch has been described the invention is not limited to such a switch, and it will be sufficient for the purposes of the invention if movement of wall 54 effects closure of any suitable switch.

A thin metal case 80 in the form of a cylinder is secured to the carrier as at 81 and has mounted thereon a lamp structure L containing a lamp 82 which is normally extinguished.

So long as proper subatmospheric pressures exist within the collector C, the bellows unit will be contracted due to its communication with the interior of the collector through the leak vent 52 and the pneumatic controller B will permit switch S to remain open. If for any reason inadequate pressures should exist within the collector for any appreciable length of time they will be communicated through the vent 52 to the interior of the bellows unit and the latter will expand because of its resilience and cause end wall 54 to press on button 75 sufficiently to close switch S. When this happens the bellows and switch, acting as a pneumatically controlled circuit closing means responsive to pressures within the collector C, will close the circuit shown in Fig. 8. The brief momentary pneumatic connection of the holder H with the collector C when lever 25 is rocked will be for too short a time to allow expansion of the bellows unit sufficient to close switch S, that is, the period of time required for enough air to pass through the vent to effect closure of the switch is longer than the interval during which the holder and collector will be pneumatically connected due to rocking of lever 25.

Contact 62 is indicated in Fig. 8 as being grounded by a wire 90, while contact 67 is connected by wire 91 to one side of the lamp 82 the other side of which is connected by wire 92 to a contact 93 in engagement with a switch blade 94 controlled by the shipper handle 95. Blade 94 is connected to the secondary 96 of a transformer T and the secondary is grounded by wire 97.

When the shipper handle is in the loom driving position shown in Fig. 8 blade 94 will engage contact 93 and the lamp can be illuminated to give a visual signal whenever switch S is closed. When the shipper handle is in the stopping position, or to the right of that shown in Fig. 8, closure of switch S will not illuminate the lamp 82. Switch S is likely to be closed during an extended period of stoppage of the loom due to leakage of air throughout the vent 52, but this will not result in continued illumination of the lamp.

When the weaver opens the cover 17 and moves it to the dotted line position indicated in Fig. 2 for removal of accumulated threads within the container there will be an immediate neutralization of the subatmospheric pressures within the container and the bellows unit will close switch S. If the weaver should leave the cover in its open position the lamp 82 will continue to burn and in doing so will call attention to the fact that the cover has not been properly closed.

In some instances it may be desirable to stop the loom in the event of failure of the vacuum system, and when this is desired a solenoid 100 may be used. As shown herein the solenoid is in parallel with the lamp 82, but if desired it can be used instead of the lamp. This solenoid may be part of a well-known knock-off mechanism more generally associated with electric warp stop motions. The knock-off mechanism includes a lever 101 rocked by a cam 102 on the bottom shaft 3, a link 103 the vertical position of which is controlled by the solenoid, a lever 104 pivoted to the link, and a rod 105 connected to the shipper handle 95. Energization of the solenoid 100 will lift the link and enable rocking of lever 101 in a counter-clockwise direction as viewed in Fig. 1 to rock the shipper handle to effect loom stoppage. Ordinarily this stopping will not be desired, but where it is employed the vent 52 may be quite small to require a considerable length of time for expansion of the bellows unit, during which time it will ordinarily be possible to open the cover, remove the contents of the container C, and close the cover before the bellows can expand sufficiently to close switch S.

From the foregoing it will be seen that the invention sets forth simple means responsive to pneumatic pressures by which failure of a pneumatic thread control system to maintain proper subatmospheric pressures will result in closure of a switch in an electric circuit containing either a lamp, or solenoid 100, or both. Momentary reduction of pressure within collector C due to rocking of lever 25 will not afford enough time for sufficient air to pass through duct 52 to effect closure of the switch. While the principal reason for failure of the pneumatic system is likely to be due to accumulation of weft ends or waste threads on the sieve or screen 47, it will be apparent that failure of the pump or the hose 42 will also effect closing of switch S. While specific forms of pneumatic thread holders and collectors have been shown for illustrative purposes, the invention is not limited to such forms, but can be used in any thread control system.

wherein failure of the system for any appreciable length of time can be relied upon to permit expansion of the bellows unit with resultant closure of switch S. The system as set forth herein is applied both to the thread holder H and a thread removing mechanism not shown but supplied with subatmospheric pressures through the pipe 41.

Having thus described the invention it will be seen that changes and modifications of the foregoing specific disclosure may be made without departing from the spirit and scope of the invention.

What is claimed as new is:

15. In a pneumatic thread control means for the reserve bobbin weft ends of a loom having a source of subatmospheric pressures and a normally open electric circuit to be closed upon failure of the control means, a pneumatic system for said weft ends in which subatmospheric pressures are created by said source, and pneumatically controlled closing means for said electric circuit responsive to pressures within said system and effective upon failure of said control means due to inability of said source to create subatmospheric pressures in said system to cause closure of said electric circuit.
20. In a pneumatic thread control means for the removal of waste threads from a loom having a source of subatmospheric pressures and a normally open electric circuit to be closed upon failure of the control means, a pneumatic system in which subatmospheric pressures are created by said source to effect removal of said waste threads, and pneumatically controlled closing means for said electric circuit responsive to pressures within said system and effective to close said electric circuit upon failure of said control means due to inability of said source to create subatmospheric pressures in said system.
25. In a pneumatic thread control means for the removal of waste threads from a loom having a source of subatmospheric pressures and a normally open electric circuit to be closed upon failure of the control means, a pneumatic system in which subatmospheric pressures are created by said source to effect removal of said waste threads, and pneumatically controlled closing means for said electric circuit responsive to pressures within said system and effective to close said electric circuit upon failure of said control means due to inability of said source to create subatmospheric pressures in said system.
30. In a pneumatic thread control means for the removal of waste threads from a loom having a source of subatmospheric pressures and a normally open electric circuit to be closed upon failure of the control means, a pneumatic system in which subatmospheric pressures are created by said source to effect removal of said waste threads, and pneumatically controlled closing means for said electric circuit responsive to pressures within said system and effective to close said electric circuit upon failure of said control means due to inability of said source to create subatmospheric pressures in said system.
35. In a pneumatic thread control means for the removal of waste threads from a loom having a source of subatmospheric pressures and a normally open electric circuit to be closed upon failure of the control means, a pneumatic system in which subatmospheric pressures are created by said source to effect removal of said waste threads, and pneumatically controlled closing means for said electric circuit responsive to pressures within said system and effective to close said electric circuit upon failure of said control means due to inability of said source to create subatmospheric pressures in said system.
40. In a pneumatic thread control means for the removal of waste threads from a loom having a source of subatmospheric pressures and a normally open electric circuit to be closed upon failure of the control means, a pneumatic system in which subatmospheric pressures are created by said source to effect removal of said waste threads, and pneumatically controlled closing means for said electric circuit responsive to pressures within said system and effective to close said electric circuit upon failure of said control means due to inability of said source to create subatmospheric pressures in said system.
45. In a pneumatic thread control means for the removal of waste threads from a loom having a source of subatmospheric pressures and a normally open electric circuit to be closed upon failure of the control means, a pneumatic system in which subatmospheric pressures are created by said source and into which the waste threads are drawn due to said pressures, said waste threads due to accumulation thereof within the system tending to prevent creation of subatmospheric pressures within the system by said source, and pneumatically controlled closing means for said electric circuit responsive to pressures within said system and effective to close said circuit when accumulated waste threads in the system causes failure of said control means by preventing the creation in said system of subatmospheric pressures by said source.
50. In a pneumatic thread control means for a loom having weft ends leading from reserve bobbins and a normally open electric circuit to be closed upon failure of the control means, a pneumatic thread holder for the weft ends, a source of subatmospheric pressures, a hollow thread collector pneumatically connected to the holder and source and in which subatmospheric pressures are created by said source to draw the weft ends from the holder into the collector, a normally open electric switch in said electric circuit, and a pneumatic controller for the switch in pneumatic communication with the collector and effective to maintain the switch in open condition if subatmospheric pressures exist within the collector but effective to close said switch upon failure of said control means due to in-

ability of said source to create subatmospheric pressures within the collector.

5. In a pneumatic thread control means for a loom having weft ends leading from reserve bobbins and a normally open electric circuit to be closed upon failure of the control means, a source of subatmospheric pressures, a pneumatic thread holder for the weft ends, a pneumatic system pneumatically connecting said source to said holder effective when the system is operating properly to enable said source to create subatmospheric pressures in the holder, a normally open electric switch in said circuit, and a pneumatic controller for said electric switch responsive to pneumatic pressures in said system and effective to close said switch and circuit upon failure of the control means due to inability of said source to maintain subatmospheric pressures in said system.

6. In a pneumatic waste thread removal means for a loom having a normally open electric circuit to be closed upon failure of the removal means, a source of subatmospheric pressures, a pneumatic waste thread removing system pneumatically connected to said source effective to draw waste threads from the loom into the system, a normally open electric switch in said circuit, a pneumatic controller for the switch responsive to subatmospheric pressures in said system, and a screen in said system intermediate the controller and said source to prevent threads drawn into the system from reaching said source, the waste threads due to accumulation on the screen tending to prevent the creation of subatmospheric pressures by said source in the system beyond said screen with reference to said source, said controller operating to close said switch and circuit upon failure of said removal means due to inability of said source to create subatmospheric pressures in the system because of the accumulation of waste threads on the screen.

7. In a pneumatic thread control means for a loom having a normally open electric circuit effective upon closure to indicate failure of the control means, a source of subatmospheric pressures, a pneumatic thread holder, a system pneumatically connecting the thread holder and the source, a pneumatic thread collector in said system intermediate the holder and source, a normally open electric switch in said circuit, and a controller for the switch in pneumatic communication with the system intermediate the holder and source effective upon failure of subatmospheric pressures in said collector to close said switch and circuit.

8. In a pneumatic waste thread control means for a loom having reserve bobbin weft ends and a normally open electric circuit effective upon closure to indicate failure of the control means, a source of subatmospheric pressures, a pneumatic thread holder for the weft ends, a pneumatic system pneumatically connecting the source and holder to create subatmospheric pressures in the latter, a waste thread collector in the system provided with a screen intermediate said source and holder, and means responsive to pneumatic pressures in the system effective upon failure of subatmospheric pressures in said system between the holder and screen due to accumulation on the latter of waste threads to effect closure of said circuit.

9. In a pneumatic waste thread control means for a loom having a normally open electric circuit effective upon closure to indicate failure of

the control means, a source of subatmospheric pressures, a pneumatic collector for the waste threads, a system pneumatically connecting the source to said collector creating subatmospheric pressures in the latter to draw waste threads into the collector, a cover for said collector normally closed but operable to permit removal of waste threads from the collector, a normally open electric switch in said circuit, and a pneumatic controller for the switch in communication with the system effective to close said switch and circuit upon failure of the control means to create subatmospheric pressures in said collector due to opening of said cover.

10. The structure set forth in claim 9 wherein said cover is provided with a screen against which the waste threads in the collector are pneumatically drawn.

11. In a pneumatic control means for the waste threads of a loom having a normally open electric circuit containing a lamp, a source of subatmospheric pressures, a collector for the waste threads pneumatically connected to and having subatmospheric pressures created therein by said source, and a pneumatically controlled closing means for said circuit responsive to pneumatic pressures within said collector normally maintaining the circuit open during the existence of subatmospheric pressures within said collector but effective upon non-existence of subatmospheric pressures in said collector to close said circuit and cause illumination of said lamp.

12. In a pneumatic control means for the reserve bobbin weft ends and waste threads of a loom provided with a normally open electric circuit which when closed gives a visual signal, a pneumatic thread holder for the weft ends, a thread collector for the waste threads, a source of subatmospheric pressures pneumatically connected to the thread holder to draw the weft ends thereinto and also pneumatically connected to the collector to draw the waste threads thereinto, and circuit closing means for said circuit responsive to pneumatic pressures in said collector maintaining the circuit open when subatmospheric pressures exist within the thread holder and collector but effective upon the non-existence of subatmospheric pressures in said thread holder and collector to close said circuit to energize said visual signal.

13. In a pneumatic control means for the reserve bobbin weft ends of a loom provided with a normally open circuit capable upon closure of giving a visual signal, a source of subatmospheric pressures, a pneumatic system for the weft ends in which subatmospheric pressures are created by said source to tension said weft ends, and pneumatically controlled circuit closing means for said circuit responsive to pneumatic pressures within the system effective to maintain said circuit open when subatmospheric pressures are created by said source within said system but effective to close said circuit upon failure of said source to create subatmospheric pressures within said system.

14. In pneumatic thread control means for the reserve bobbin weft ends of a loom which is stopped upon energization of a solenoid due to closure of a normally open electric circuit, a source of subatmospheric pressures, a pneumatic system for the weft ends in which subatmospheric pressures are created by said source to tension said weft ends, and pneumatically controlled closing means for said circuit normally effective to maintain the circuit open when said source

maintains subatmospheric pressures within the system but effective upon failure of said source to maintain said subatmospheric pressures in said system to close said circuit and effect stoppage of the loom.

15. In a pneumatic thread control means for the reserve bobbin weft ends of a loom having a source of subatmospheric pressures and a normally open electric circuit to be closed upon failure of the control means, a pneumatic thread collector pneumatically connected to said source and having subatmospheric pressures created therein by said source, a pneumatic thread holder for the weft ends normally pneumatically disconnected from the collector but periodically connected pneumatically to the collector for brief intervals, a normally open electric switch in said circuit, and a controller for said switch responsive to subatmospheric pressures and communicating with said collector and operative to close said switch upon failure of the control means due to absence of subatmospheric pressures within said container for a period of time greater than one of said intervals.

16. In a pneumatic thread control means for the reserve bobbin weft ends of a loom having an electric circuit to be closed upon failure of the control means, a source of subatmospheric pressures, a pneumatic thread collector in which subatmospheric pressures are created by said source, a pneumatic thread holder for the weft ends normally pneumatically disconnected from said collector but periodically connected pneumatically to the collector for brief intervals, and pneumatically controlled circuit closing means for said circuit responsive to pneumatic pressures within said collector and normally maintaining the circuit open but effective to close said circuit upon failure of the control means due to absence of subatmospheric pressures within the collector for a period of time longer than one of said intervals but ineffective to close the circuit when said collector and holder are pneumatically connected during said intervals.
